LOCKING DEVICE FOR INTERLOCKING SWITCH STANDS

Filed April 6, 1925

Fig. 2.

Patented Sept. 22, 1925.

1,554,545

UNITED STATES PATENT OFFICE.

FRANK C. ANDERSON, OF CINCINNATI, OHIO, ASSIGNOR TO THE AMERICAN VALVE AND METER COMPANY, OF CINCINNATI, OHIO, A CORPORATION OF OHIO.

LOCKING DEVICE FOR INTERLOCKING SWITCH STANDS.

Application filed April 6, 1925. Serial No. 21,057.

To all whom it may concern:

Be it known that I, FRANK C. ANDERSON, a citizen of the United States, residing at Cincinnati, in the county of Hamilton and State of Ohio, have invented certain new and useful Improvements in Locking Devices for Interlocking Switch Stands, of which the following is a specification.

My invention relates to switch-stands, and 10 more especially to switch-stands provided with interlocking mechanism, as for example like those disclosed and claimed in my prior Patents No. 1,141,905, dated June 1, 1925, or No. 1,234,522, dated July 24, 1917, 15 or in my copending applications, Serial No. 732,218, filed August 15, 1924, Serial No. 737,149, filed September 11, 1924, Serial No. 739,113, filed September 22, 1924, and Serial No. 750,153, filed November 15, 1924, on 20 which my present invention is an improvement.

The object of my invention, in common with that of the devices of the aforementioned applications, is to lock the interlocking mechanism directly instead of indirectly by virtue of its connection to the switch-throwing lever as in the aforementioned patents; thereby indirectly locking the switch-throwing lever but providing for 25 leaving the interlocking mechanism safely locked should the switch-stand proper, with its throwing lever, be torn away from the interlocking mechanism in an accident such as may result from a projecting object on a 30 train striking the stand, or some object struck by the train, as a vehicle, being thrown thereby against the stand. An especial object of my present invention is to simplify the construction and to increase 35 the security of any of the devices of that character. Other objects will appear in the 40 course of the ensuing description.

I attain these objects by the device illustrated, for example, in the accompanying 45 drawing, in which—

Figure 1 is a general perspective view of 50 part of a switch and a switch-stand connected thereto and having an interlocking mechanism with my invention applied thereto;

Fig. 2 is a vertical longitudinal section, on 55 the plane of the line 2—2 of Fig. 4, of the interlocking mechanism with my invention embodied therein;

Fig. 3 is a detail perspective view of the

interlocking plunger and its rack, constructed according to my invention; and

Fig. 4 is a front end elevation of the locking mechanism, only part of the interlocking bar being shown. 60

Although my present invention is applicable to any of the devices of the prior patents and applications before mentioned, I have exemplified its use, herein, with a high switch-stand similar to that of my first 65 above mentioned prior patent, in which the switch-stand frame 1 has the upright target shaft 2 in upper and lower bearings 3 and 4, with the switch-connecting rod 5 connected to the shaft 2 by a crank as is well known in 70 the art, and connected to the point rails of the switch, only one of which rails 6 is shown, by a bar 7. Above the upper bearing 4 the fulcrum-head 8 is fixed on the target shaft 2 and has the switch-throwing lever 9 75 swinging up and down on the pivot 10 transversely through the head 8 and adapted to enter the slot 11 when the switch is closed with the point rail 6 against the stock rail 12, at which time the lever 8 hangs vertical, 80 as shown, and has an ear 13 projected past the end of the fulcrum-head 8, to receive a padlock for locking the switch. Although 85 my present invention provides for locking elsewhere, I prefer still to provide the stand with this means for locking the lever 9 directly, so that it is available in cases wherein my other locking means is not used with the stand.

The pivot 14 projects out from the frame 90 1 toward the track at such location that the pivot 10 of the lever 9 is alined with it when the switch is closed as shown, and a short arm 15 swings on this pivot 14 and carries a pin 16 engaged in a hole in the lever 9, so 95 that the arm 15 is swung up or down with the lever 9 when bringing the latter out of or into the slot 11; it being understood that this pin 16 is released from the lever 9 when it is swung around to open the switch, as 100 fully set forth in my Patent No. 1,141,905, above mentioned. This pin 16 projects toward the track, and the upper end of the connector 17 is pivoted thereon, to connect 105 with the interlocking mechanism, which now will be described.

This mechanism comprises the housing 18 set into a gain in one of the head blocks that support the stand, with a stirrup 19 110 projecting outside the head block and hav-

ing sliding through this stirrup the interlocking bar 20, with an opening through which the interlocking plunger 21, sliding in the housing 18, is adapted to extend when the opening registers with the openings in the casing and stirrup. This bar 20 extends under the stock rail 12 and has its end connected by means of a suitable plate 22 to the end of the point rail 6, so that the bar 20 must move with the point rail, in such a manner, as in my above mentioned prior devices, that if for any reason the point rail 6 is not brought safely close to the stock rail 12 by the switch-throwing mechanism, the openings in the bar 20 and the casing or housing 18 and stirrup 19 cannot register, and the plunger 21 cannot enter the opening of the bar 20.

For sliding this plunger 21, a crank is provided, comprising the shaft part 23 journaled in the upper part of the housing 18, with two arms 24 extending down inside the housing near opposite lateral walls thereof, and with two arms 25 extending back past the rear recessed end of the housing, just outside said walls. The rear ends of these latter arms 25 are pivoted to the lower end of the connector 17. The plunger 21 is mounted, at its rear end inside the housing 18, in two downwardly extending lugs on the rack 26, which has, at each side, two laterally projecting lugs 27. The downwardly extending arms 24 of the crank straddle the rack 26, and the lower end of each of these arms 24 fits between a respective pair of the lugs 27. The rearwardly extending rod 28, fixed in the upper part of the rear end of the rack 26 and projecting out through the back of the housing 18, is for connection of a signalling device to the interlocking mechanism, and does not form an essential part of the present invention.

With the parts connected as just described, when the switch-throwing lever 9 is raised out of the slot 11, to horizontal position, for throwing the switch, the plunger 21 is completely withdrawn from the opening in the bar 20, permitting the bar 20 to move with the point rail 6 as the latter is moved away from the stock rail 12 by swinging the lever 9 and the fulcrum-head 8 around in the horizontal plane, the same as in any of the prior devices mentioned.

My present improvement consists in providing for locking the interlocking plunger 21 against this withdrawal from the interlocking bar 20, by locking it directly to a part of the interlocking housing 18. As herein exemplified, and as I prefer to make this provision, the rack 26 of the plunger 21 has the upwardly and forwardly extending neck 29 above the plunger 21, on the front end of which neck 29 is the ear

30 which projects out through a slot 31 in the front end of the housing 18 just down from the top thereof, when the plunger 21 is engaged in the bar 20, so that its opening 32 is out past the outer front surface of the housing 18 to receive the bow of a padlock 33 as seen in Fig. 1. When thus locked, the padlock prevents the plunger 21 from receding back out of the bar 21, which thus cannot slide, and being connected to the switch rails, these cannot be thrown by means of the switch-throwing mechanism.

When locked in this manner, if the switch-stand frame 1 and parts carried thereby are torn away, the plunger 21 cannot be pulled therewith from its engagement with the bar 20; so that the switch remains locked, although the entire upper mechanism is disrupted. The interlocking device, being very low, and most of it being embedded in the head block, hardly can be engaged by a disrupting object in such a manner as to tear it from its position. Thus, the switch is locked with much greater security against such accidents than when it is locked up in the ear 13. This arrangement also protects the switch in such cases as accidental disconnection of the switch-throwing mechanism from the switch rails. For example, if the bolt connecting the rod 5 and bar 7 breaks or drops out, the switch rails might be jarred over, derailing a train, if the locking is at the ear 13. With the rails locked in closed position at the plunger 21, that disconnection does not endanger the traffic, because the bar 20 still holds the rails.

Furthermore, incomplete throwing of the switch by means of the switch-throwing mechanism, either through looseness or disconnection of its parts or inattention of the switchman, cannot be followed by a locking of the switch, as may be possible if the locking is done at the ear 13. Because the opening in the interlocking bar 20 must register with the plunger 21, allowing the latter to enter, before the ear 30 can project its opening 32 for reception of the padlock, the switchman cannot place the padlock until the switch rails are in safe relation. This assurance was largely provided in my prior patents mentioned, locking the switch-throwing mechanism; but direct application of the lock to the interlocking plunger increases it. Also, as compared with application of the lock to some part pivotally or slidably related to the plunger, as in my prior applications mentioned, the assurance is increased, because the factor of improper relation of the parts, through wear or damage, is removed; and, the locking being still lower on the mechanism than in any of those devices, the chance for disruption by striking of objects against the mechanism is correspondingly reduced. In addition, the

device is simplified by elimination of one or more moving parts.

The housing 18 is made with an open top, closed by the cover 18', bolted thereto by means of the studs 18''; the crank having its shaft part 23 journaled one half in the housing body and one half in the cover 18', while the slot 31 for the ear 30 opens out through the top of the housing body and has its upper end closed by the cover 18'. This construction permits simple integral formation of the crank shaft 23, and arms 24 and 25, as the crank can be dropped into its lower bearing section before placing the cover 18', previously to which the rack 26 has been placed in the housing easily, by dropping its ear 30 down into the slot 31.

Although I have exemplified use of my present improvement with the high stand, 20 and with the mechanism connected to the switch-throwing lever directly by the connector 17, as in my first mentioned prior application, it will be understood that it is equally applicable to and a benefit in the 25 interlocking mechanisms of the other three prior applications mentioned, all of which provide for a movement of the plunger before the switch can be thrown, or an opposite movement of the plunger before it can 30 be locked. The modifications chiefly concern the crank to operate with different types of switch-throwing mechanisms, or to operate in different manners, and in any of these my present direct-locking provision 35 being adaptable thereto by providing a suitable extension on the plunger for reception of the lock, and the movable parts for coaction with a lock, on top of the housing, thereby being eliminated. These and other 40 modifications may occur, and therefore, while I have specifically illustrated and described a certain example of application of my invention, I do not wish to be understood as being limited to such precise disclosure, but what I claim as new and desire 45 to secure by Letters Patent is:

1. In a switch-stand, in combination with a switch-throwing element thereof and interlocking mechanism therefor, having an operative connection to said element, means adapted to receive a padlock for locking said interlocking mechanism directly and thereby indirectly locking said switch-throwing element.
- 55 2. In a switch-stand, in combination with a switch-throwing element thereof and interlocking mechanism therefor comprising a plunger having an operative connection to said element, means fixed to said plunger adapted to receive a padlock for locking said interlocking mechanism directly and thereby indirectly locking said switch-throwing element.
- 60 3. In a switch-stand, in combination with a switch-throwing element thereof and in-

terlocking mechanism therefor comprising a housing and a plunger sliding in said housing and having an operative connection to said element, means fixed to said plunger inside said housing and slidably extending outside said housing, adapted to receive a padlock to engage against the exterior of the housing for locking said interlocking mechanism directly and thereby indirectly locking said switch-throwing element. 75

4. In a switch-stand, interlocking mechanism comprising a plunger, and means fixed to said plunger adapted to receive a padlock for locking said interlocking mechanism. 80

5. In a switch-stand, interlocking mechanism comprising a housing, a plunger sliding in said housing, and means fixed to said plunger inside said housing and slidably extending outside said housing, adapted to receive a padlock to engage against the exterior of the housing. 85

6. In a switch-stand, interlocking mechanism comprising an interlocking bar, a plunger slideable to engage said bar, and means fixed to said plunger adapted to receive a padlock adjacent to the place of engagement of said plunger with said bar, for locking said interlocking mechanism. 90

7. In a switch-stand, interlocking mechanism comprising an interlocking bar, a housing guiding said bar, a plunger slideable in said housing to engage said bar, and means fixed to said plunger inside said housing and slidably extending outside said housing, adapted to receive a padlock to engage against the exterior of the housing adjacent to the place of engagement of said plunger with said bar, for locking said interlocking mechanism. 100

8. In a switch-stand, interlocking mechanism comprising a housing, a plunger slideable in said housing, a rack fixed to said plunger inside said housing, and a neck on said rack having an ear extending out through a wall of said housing. 110

9. In a switch-stand, interlocking mechanism comprising a housing and a separate cover for said housing secured thereto, a plunger slideable in said housing, a rack fixed to said plunger inside said housing, and a neck on said rack having an ear, said housing having a slot in its wall over said plunger, with an open upper end closed by said cover, and said ear slidably extending out through said slot. 115

10. In a switch-stand, interlocking mechanism comprising a plunger, a crank having an arm in operative relation with said plunger and an arm in operative relation with the switch-throwing mechanism of the switch-stand, and means fixed to said plunger adapted to receive a padlock for locking said plunger and thereby locking said switch-throwing mechanism. 125

11. In a switch-stand, in combination with a switch-throwing element thereof and interlocking mechanism therefor, having an operative connection to said element, means below said operative connection adapted to receive a padlock for locking said interlocking mechanism directly and thereby indirectly locking said switch-throwing element.
  - 10 12. A rack for switch-interlocking plunger comprising an upwardly and longitudinally extended neck having a lock-receiving aperture.
  - 15 13. A rack for a switch-interlocking plunger having pairs of lateral projections on its opposite sides, and having extending upwardly and longitudinally from one end
- thereof a neck having a lock-receiving aperture.
14. In switch-interlocking mechanism, a rack, a plunger extending from said rack, and a neck extending from said rack substantially parallel with said plunger and having near its end a lock-receiving aperture. 20
15. In switch-interlocking mechanism, a rack, a plunger extending from one end of said rack near the bottom thereof, and a neck extending from said end above and substantially parallel with said plunger and having near its end a lock-receiving aperture. 25
- 30

FRANK C. ANDERSON.
